UNITED STATES PATENT OFFICE.

NEWTON HOLDEN, OF NEW YORK, N. Y., ASSIGNOR TO HOLDEN ONE MAN TOP COMPANY,
INC., A CORPORATION OF NEW YORK.

FOLDING TOP FOR VEHICLES.

1,147,091.

Specification of Letters Patent. Patented July 20, 1915.

Application filed October 18, 1913. Serial No. 795,861.

To all whom it may concern:

Be it known that I, NEWTON HOLDEN, a citizen of the United States, and a resident of New York, in the county of New York 5 and State of New York, have invented certain new and useful Improvements in Folding Tops for Vehicles, of which the following is a specification.

This invention relates to folding tops for 10 vehicles, particularly tops of this character used on automobile touring cars, wherein it is desirable to have an unobstructed view.

The principal object of this invention is 15 to make a folding top with a long outrigger bow in a very simple form requiring a minimum of parts to secure proper folding action and support for the outrigger bow. To this end I form the outrigger bow with a break joint opening downward, and adjacent to the joint I pivot to the portions of 20 the outrigger bow, links jointed together at their free ends with a joint opening upward. When the bow is unfolded and fastened in position over the vehicle the links and the 25 portions of the outrigger bow are substantially in alinement thus forming a rigid construction without any other additional support aside from the fabric of the top itself.

In the drawing illustrating this invention, 30 Figure 1 is a diagrammatic elevation illustrating the top as unfolded and fastened in place. Fig. 2 is a similar view of the top folded. Fig. 3 is a diagram of the top detached illustrating the parts in intermediate 35 position. Fig. 4 is a fragmental detail elevational view illustrating the means used for breaking the joint of the outrigger bow. Fig. 5 is a fragmental detail sectional view illustrating the means used for breaking the 40 joint of the outrigger bow. Fig. 6 is a diagrammatic view similar to Fig. 3 illustrating a modified form for use with larger vehicles.

Referring to Figs. 1 to 5 inclusive, the 45 improved top consists of a main bow 10 to which is pivoted an intermediate bow 11. Extending rearwardly of the intermediate bow is an auxiliary bow 12, and extending forwardly from the intermediate bow is the 50 outrigger bow which extends to the front of the vehicle without obstructing any of the view. This outrigger bow is formed of two portions 13 and 14, joined or hinged at 15, with a break joint which breaks downward 55 only. Adjacent to the joint are pivoted to

each of the portions 13 and 14 the links 13 and 17 having their free ends joined at 18 with a break joint breaking upward only. The length of these links is substantially equal to the distance of their pivots upon 60 the respective portions of the outrigger bow, from the joint 15.

Pivoted at the joint 18 is another auxiliary bow 19 which supports the fabric between the intermediate bow and the end of the 65 outrigger. The latter is fastened down and held in place by any suitable means. Preferably I fasten the same to the wind shield 20 or to some projection extending from the 70 same.

When the top is unfolded and fastened as shown in Fig. 1, the links 16 and 17 come into substantial alinement with the portions 13 and 14 of the outrigger bow forming a rigid unit from the end of the outrigger 75 bow to its point of connection with the intermediate bow. The tension of the material downward upon the auxiliary bow 19 tends to depress the joint 18 and thus raise the joint 15, as will be readily understood. 80

To facilitate the unfolding of the top, I provide means for breaking the joints 15 and 18, opening the former downward and the latter upward to make it possible for the operator to finish the folding by simply 85 throwing backward the forward portion 14 of the outrigger bow. This means consists preferably of a rotatable member, as a cam 21 journaled upon a boss 22 extending preferably from one of the portions of the outrigger bow as the portion 13. This cam is rotated by a handle 23 extending to a suitable point within reach of the operator and engages the opposing link 16 to raise the same sufficiently to open the joint 18 upward and the joint 15 downward, whereupon the further unfolding may be accomplished by throwing over the outrigger bow 95 as previously described.

In the modified form illustrated in Fig. 6, 100 the main bow 30 has pivoted thereto the intermediate bow 31 which has mounted thereon the auxiliary bow 32 and extending forwardly therefrom is the outrigger bow comprising the portions 33 and 34. Pivoted to 105 these portions of the outrigger bow, adjacent to the break joint 35, are the links 36 and 37 having a break joint 38 which opens upward only. These links have extensions 39 and 40 at the other side of their 110

joint and to the ends of these links are pivoted the auxiliary bows 41 and 42. Through this construction providing for one additional auxiliary bow, greater length of the 5 outrigger may be used while still securing proper support for the material.

If the vehicle is not supplied with a wind 10 shield, a special support may be formed for the top which may also be attached to the dashboard substantially in the same manner as the wind shield is attached. This support may consist of a foot 43 pivoted to the end of the forward portion of the outrigger and swinging backward out of the way 15 when the top is folded.

It will thus be seen that I have provided a folding top which is simple in construction and requires a minimum of parts to secure the proper support of the outrigger bow 20 when unfolded and to obtain an easy folding action.

Various modifications may be resorted to without departing from the scope of the invention, as set forth in the accompanying 25 claims.

Having thus described my invention, I claim as new and desire to secure by Letters Patent:

1. A folding top for vehicles comprising a 30 main bow, an intermediate bow and an outrigger bow extending from the intermediate bow, said outrigger bow having a break joint opening downward at an intermediate point thereof, links pivoted to the portions 35 of the intermediate bow adjacent its break joint, said links being jointed together with a joint opening upward only, an auxiliary bow pivoted to the links at their joint and means for securing the forward portion of 40 the outrigger bow in unfolded position.

2. A folding top for vehicles comprising a main bow, an outrigger bow extending forwardly freely therefrom, said outrigger bow being formed with a break joint opening 45 downward at a point intermediate the ends thereof, links pivoted to the portions of the outrigger bow at each side of the break joint, said links having their free ends connected with a stop joint opening upward 50 only, said links being of a length such as to come into substantial alinement with the outrigger bow when the top is set up.

3. A folding top for vehicles comprising a main bow, an outrigger bow extending forwardly therefrom, said outrigger bow being formed with a break joint intermediate its 55 ends opening downward, links pivoted to the

portions of the outrigger bow adjacent to the break joint at each side thereof, said links being jointed together with a break joint opening upward only and the length of said links being substantially equal to the distances of their points of connection with the outrigger bow to the break joint thereof, said links being adapted to come 60 into substantial alinement with the outrigger bow when the same is unfolded, and an auxiliary bow mounted upon the links.

4. A folding top for vehicles comprising a main bow, an outrigger bow extending forwardly therefrom, said outrigger bow being formed with a break joint intermediate its 70 ends opening downward, links pivoted to the portions of the outrigger bow adjacent to the break joint at each side thereof, said 75 links being jointed together with a break joint opening upward only and the length of said links being substantially equal to the distances of their points of connection with the outrigger bow to the break joint thereof, 80 said links being adapted to come into substantial alinement with the outrigger bow when the same is unfolded, an auxiliary bow mounted upon the links and means for breaking the joints of the outrigger bow and 85 the links to secure the initial unfolding.

5. A folding top for vehicles comprising a main bow, an outrigger bow extending forwardly therefrom, said outrigger bow being formed with a break joint intermediate its 90 ends opening downward, links pivoted to the portions of the outrigger bow adjacent to the break joint at each side thereof, said 95 links being jointed together with a break joint opening upward only and the length of said links being substantially equal to the distances of their points of connection with the outrigger bow to the break joint thereof, said links being adapted to come into substantial alinement with the outrigger bow 100 when the same is unfolded, an auxiliary bow mounted upon the links and a cam mounted upon one of the members of the quadruple formed by the outrigger bow and the links for breaking the joints to secure the initial 105 unfolding.

Signed at New York, in the county of New York and State of New York, this 6th day of October, A. D. 1913.

NEWTON HOLDEN.
